(57) **ABSTRACT**

A discardable cartridge having a limited quantity of a lip balm that is loaded into a closable applicator container, such as a piece of jewelry or a wearable accessory. The cartridge includes a rigid or resilient upper base having a convex or flat top surface upon which the lip balm is associated, and a volume of lip balm attached to the top surface of the base. The flat or convex top surface allows wiping the balm onto the lips single-handedly. The top surface of the cartridge can include a plurality of integrally-attached bristles, between which the lip balm is embedded, anchoring the lip balm to the cartridge, and providing the additional function of exfoliation.

CARTRIDGE FOR AN APPLICATOR
CONTAINERCROSS-REFERENCE TO RELATED
APPLICATIONS

This application claims the benefit of US Provisional application 62/393,264, filed Sep. 12, 2016, the disclosure of which is incorporated by reference in its entirety.

FIELD OF THE INVENTION

The present invention relates to an applicator container for a personal care composition.

BACKGROUND OF THE INVENTION

Personal care compositions, particularly lip balm and lip gloss, are well-known commercial products that are typically used by both men and women. Many versions of these products in the marketplace have several shortcomings. Some dispensers and applicators are so small that they are easily lost, and they can be misplaced in a purse, backpack, vehicle, or jacket. Other dispensers and applicators are often bulky and awkward to store in either a small purse or pocket. In some public places, regulations or rules may prevent bringing a bag to store the dispenser or applicator, and in some circumstances, the dispensers or applicators can even be prohibited. Even when a particular dispenser or applicator can be conveniently transported in an appropriately-sized bag or pocket, they can often become unsanitary after several applications of the personal care composition.

In light of all of the above issues, several devices have been developed to provide portable versions of common personal care compositions, and have been disclosed in U.S. Pat. Nos. 6,283,658, 7,309,185, 7,785,026, and 8,747,002, and U.S. Pat. Pubs. 2012/0234336 and 2013/0014312, the disclosures of which are incorporated by reference in their entireties.

SUMMARY OF THE INVENTION

The present invention provides an article of manufacture as a limited-use, personal care product in an applicator container, comprising a cartridge containing a volume of a personal care composition that can be loaded into a closable applicator container. When the personal care composition has been depleted from the loaded cartridge after a limited use time or number of uses, the cartridge can be unloaded, discarded, and replaced by a fresh, new cartridge.

The invention also includes a cartridge for a personal care composition, comprising: a) a rigid or resilient body including an upper base having a top surface that has a flat, planar or convex shape; b) a volume of personal care composition attached to the top surface of the upper base; and c) a means for securing the cartridge body releasably into the receptacle of a separate applicator container. The maximum height of the volume of personal care composition is less than or equal to the maximum length of the cartridge base, where the height of the personal care composition is measured from the uppermost surface of the upper base. Typically, this is measured from the center of the top surface. When a cartridge is secured inside the receptacle of an applicator container, the top surface of the upper base is flush with, or slightly raised above, the upper rim of the applicator container so that the entire personal care composition attached to the surface of the cartridge can be applied.

2

In another embodiment of the invention, the personal care composition is an external-use, non-ingestible substance selected from a group consisting of a cosmetic, therapeutic, hygienic, and skin-care composition.

5 In a further embodiment of the invention, the personal care composition is lip balm.

In another embodiment of the invention, the cartridge body, the top surface of the upper base, and the personal care composition are essentially coaxial with one another around a common axis.

In a further embodiment of the invention, the cartridge is symmetrical around the common axis.

15 In an embodiment of the invention, the personal care composition disposed on the upper base's top surface can be swiped with one hand, or single-handedly, across the lips or other body part.

20 In another embodiment of the invention, the invention includes a cartridge useful for containing a personal care composition, comprising: a) a rigid or resilient body including a base having a top surface, b) a plurality of integrally-attached, resilient protuberances extending from the top surface of the base, and c) an optional means for securing the body of the cartridge releasably into a receptacle of a separate applicator container. Each of the protuberances is attached integrally at a base end of the protuberance to the top surface of the cartridge. The top surface of a cartridge base with integrally-attached protuberances can be flat, planar, convex, or concave. The lengths of each of the 25 protuberances can be constant or varied so that their distal ends form a contact surface from which to apply a personal care composition. The contact surface defined by the distal ends of each of the plurality of protuberances can be flat, domed, angled, or variable. The cartridge can be secured 30 inside any applicator container configured to receive the cartridge, including applicator containers that have sidewalls that extend above the top surface of the cartridge.

35 In a further embodiment of the invention, the plurality of protuberances is comprised of a plurality of silicone bristles.

40 In further embodiment of the invention, a personal care composition can be embedded between each of the protuberances, anchoring the personal care composition to the base of the cartridge. Personal care compositions can be embedded between the protuberances either before or after the cartridge is secured inside an applicator container.

45 In an embodiment of the invention, the cartridge body has a bore formed axially into the plug, and can extend axially through the body. In one particular embodiment, the bore extends through from a bottom surface of the plug, to the top surface of the upper base, to define an opening there between. In one aspect of the invention, the bore provides a cavity into which the surrounding material of the plug to can expand when the plug is being pressed into a capturing bore or void that provides a receptacle for the cartridge in an the 50 applicator container. In another aspect, the bore serves as a vent for the escape of any air or gases that might become trapped near the top surface of the upper base when a volume of personal care composition is placed onto the top surface.

55 In another embodiment of the invention, a cartridge can further include a covering that envelops and protects the personal care composition from debris and other contaminants, which can be removed and discarded prior to insertion of the cartridge into the receptacle of the applicator container, or after insertion of the cartridge and prior to the first application of the personal care composition on the lips or skin of the user. The covering can be reusable or discardable.

In a further embodiment of the invention, the covering further includes a rigid or resilient cap that can be frictionally or mechanically secured to the cartridge base or personal care composition. Exemplary mechanical securements can include snap beads and detents, complementary screw threads, a mounting post and slot mechanism, and a lever and a catch. The cover can also include one or more protecting wraps that can temporarily secure the lower rim of a cap to the perimeter edge of a cartridge base.

In a further embodiment of the invention, the cap is closed on one end by an upper wall, and includes a cylindrical sidewall and at least one cap projection that extends axially from an inside surface of the upper wall, that extends into the personal care composition when the cap is secured to the upper base of the cartridge or the personal care composition. The cap projection can provide a rigid body through which a user can apply pressure to frictionally fit a cartridge inside a receptacle of an applicator container without damaging the personal care composition.

In another embodiment of the invention, the means for securing the cartridge body into an applicator container further includes a receptacle in the applicator container that is configured to receive and retain the body of the cartridge within the receptacle.

In a further embodiment of the invention, the receptacle has an annular interior sidewall and the cartridge body includes a plug having an annular wall that frictionally engages with a portion of the annular interior sidewall of the receptacle, securing the cartridge inside the receptacle of the applicator container. Alternatively, the cartridge body can have a receptacle that has an annular interior sidewall and the applicator container can have a plug having an annular wall that frictionally engages with a portion of the annular interior sidewall of the receptacle on the cartridge body, securing the cartridge inside the applicator container.

In a further embodiment of the invention, the cartridge body can be secured into an applicator container by a mechanical fastener. Exemplary mechanical fasteners include a slide and track mechanism, a finger latch mechanism, a mounting post and receiving slot mechanism, complimentary screw threads, a lever and catch, twist lock closures, a pair of magnets of opposite polarity, a hook material and a loop material, or snap beads and snap detents.

In another embodiment of the invention, the applicator container is a closable applicator container that includes a closure that is removable from its position over the receptacle. The closable applicator container can also include a fastener comprising a first fastener element on the receptacle, and a second fastener element on the removable closure, to releasably fasten the removable closure to the receptacle. When the removable closure is unfastened, the personal care composition within the cartridge is uncovered and revealed.

In a further embodiment of the invention, the user can swipe and apply a portion or any remaining portion of the entire volume of personal care composition, unimpeded by the removed closure. The unfastened removable closure can be separable from the closable applicator container, or a portion of the closure can remain attached to the closable applicator container, such as with a hinge, while the user accesses and applies the personal care composition. The fastener can be selected from the group consisting of a lever and catch, kiss locks, a twist lock closure, a mounting post and post-receiving slot mechanism, a snap stud and snap socket, snap beads and snap detents, a buckle and clasp, a hook material and a loop material, complementary screw threads, and a pair of magnets of opposite polarity.

In another embodiment of the invention the closable applicator container can dispense and apply substantially all of the composition from the surface of the cartridge, without needing to or requiring dipping a finger down into the receptacle or cartridge.

In another embodiment of the invention, the closable applicator container can be configured to store the cartridge when not in use.

In another embodiment of the invention, the closable applicator container can further include an outer wall, a portion of which is elliptical or oval-shaped. The elliptical or oval-shaped portion of the outer wall defines an elongate or arcuate gripping surface that facilitates single-handed operation of the closable applicator container. The elliptical or oval-shaped portion of the outer wall can be configured to fit between the base of the user's thumb and forefinger and enable the applicator container to rest flat against a user's chest when the closable applicator container is worn as a necklace or locket.

In another embodiment of the invention, the closable applicator container can be a piece of jewelry or wearable accessory.

A further embodiment of the invention is a cartridge and an applicator container for a personal care composition that are configured to be handled and be applied by a user with one hand, or single-handedly, or both hands, and without the user touching the personal care composition with a finger when applying.

In another embodiment of the invention, the cartridges can be configured to be loaded into commonly-available applicator containers, including but not limited to lip balm tubes, lipstick applicators, makeup or cosmetic containers, and other dispensing apparatuses. Cartridges can also be configured to be loaded and secured within the applicator containers of commercially-available personal care products, particularly lip balm products, to recharge the applicator container after its contents have been depleted.

In another embodiment of the invention, the applicator container further includes an ejector for controllably ejecting the cartridge from the applicator container. Ejectors can be selected from a group consisting of a threaded rod and turnwheel or an elevator platform.

Known applicator containers do not permit the entire quantity of a personal care composition, particularly lip balm, to be dispensed from its dispensing container, either because the composition must either be dispensed or squeezed out of an internal container or housing, or it is loaded into a receptacle where much of the composition is below the surface of what can actually be applied. Where only a small quantity of personal care product is provided, the large amount of wasted material limits the composition's utility. The cartridge of the present invention can hold a small quantity of a personal care composition (such as a day's supply or less than ten applications), and the entire quantity can be used or applied with little or no waste. The composition can be housed in a closable applicator container, such as a piece of jewelry, for ease of transport and to prevent the cartridge, composition, or container from becoming unsanitary over time.

These and other objects and features of the present invention will become apparent to one skilled in the art from the following description and accompanying drawings. It is to be understood that the drawings are designed for illustration purposes only and are not intended to define the limit or scope of the present invention.

BRIEF DESCRIPTION OF THE DRAWINGS

The embodiment, aspects and advantages of the invention other than those set forth above will become apparent when

consideration is given to the following detailed description thereof. Such description makes reference to the annexed drawings.

FIG. 1 is a top perspective view of a cartridge including an upper base that has a flat top surface.

FIG. 2 is a top perspective view of another embodiment of a cartridge including an upper base that has a convex top surface.

FIG. 3 is a top perspective view of the cartridge in FIG. 1 with a personal care composition attached to the flat top surface.

FIG. 4 is an exploded perspective view of a personal care product of the present invention that includes a sanitary cap, a cartridge, and an applicator container having a receptacle configured to receive the cartridge.

FIG. 5A is a top perspective view of the personal care product of FIG. 4 according to the present invention in which the cartridge is secured inside the receptacle of an applicator container.

FIG. 5B is a sectional view of the personal care product in FIG. 5A, taken through line 5B-5B.

FIG. 6 is a top perspective view of an empty cartridge with a plurality of protuberances integrally attached to the top surface of the cartridge.

FIG. 7A is a top plan view taken of the empty cartridge in FIG. 6 showing an exemplary arrangement of the plurality of protuberances on the top surface of the cartridge.

FIG. 7B is a top plan view of an alternate arrangement of the plurality of protuberances on the top surface of a cartridge.

FIG. 7C is a top plan view of a further alternate arrangement of the plurality of protuberances on the top surface of a cartridge.

FIG. 8A is a sectional view taken along line 8A-8A of the cap shown in FIG. 4 for a personal care composition.

FIG. 8B is a sectional view taken along line 8B-8B of the cap shown in FIG. 4 secured to a cartridge base and enveloping a personal care composition.

FIG. 8C is a sectional view of an alternate embodiment of a cap that can be used to envelop a personal care composition, secured to a cartridge base.

FIG. 8D is a sectional view of yet another alternate embodiment of a cap that can be used to envelop a personal care composition, secured to a cartridge base by a protective wrap.

FIG. 9 is a sectional view of a personal care product according to the present invention that includes a cartridge having a personal care composition embedded between a plurality of integrally-attached protuberances, secured inside the receptacle of an applicator container.

FIG. 10 is an exploded perspective view of an alternative embodiment of a personal care product of the present invention and an exemplary cover that can be releasably fastened to the applicator container.

FIG. 11 is a sectional view of a locket formed by fastening a removable cover to the applicator container, with a cartridge secured inside the applicator container.

DETAILED DESCRIPTION OF THE INVENTION

The present invention relates to a disposable cartridge that includes a limited quantity of a personal care composition. The cartridge can include a rigid or resilient upper base having a top surface that is flat, planar, or convex; a volume of personal care composition attached to the top surface of the upper base, and a means for mechanically or frictionally

securing the cartridge releasably into a closable applicator container, which can be configured to store the cartridge when the personal care composition is not being used. Once the volume of personal care composition has been depleted completely, the empty cartridge can be unloaded, discarded, and replaced by a fresh, new cartridge. Similarly, a cartridge having a volume of personal care composition can be transferred from one applicator container to another applicator container without affecting the quantity or utility of the personal care composition attached to the cartridge.

The cartridge base can be made of any rigid or resilient material, including but not limited to metallic or thermoplastic materials, or inert synthetic polymers, such as polysiloxane, which is commonly referred to as silicone. FIG. 1 illustrates an empty cartridge 10 including a body 9 that includes an upper base 12 that has a flat top surface 14. The body can include a plug 11 and can extend perpendicular to the upper base 12, or the plug 11 can be configured into two or more segments 11a, 11b, and 11c that taper inward to facilitate a frictional fit inside the receptacle of an applicator container.

In an embodiment of the cartridge 10, the body has a bore 16 formed axially into the plug 11. The bore 16 can be a cylindrical bore, and can extend along the centerline axis of the body. The bore 16 extends through a bottom surface 15 of the plug 11 to define an opening 18, and a distal end of the bore 16 extends into the upper base 12. In the illustrated embodiment, the bore 16 extends through both the top surface 14 of the upper base 12 and the bottom surface 15 of the plug 11, to define both an opening 17 in the top surface 14 of the upper base 12, and the opening 18 in the bottom surface 15 of the plug. In another embodiment of the invention, the bore 16 can be positioned radially away from the centerline axis 100 of the plug and upper base 12, while in another embodiment, there can be two or more bores, spaced apart along the top surface 14 of the upper base 12. The bore 16 is typically slightly tapered along its axial to aid in the molding process. In one aspect of the invention, the bore 16 provides a cavity into which the surrounding material of the plug 11 can expand elastically when the plug 11 is being pressed into a capturing bore or void 54 that provides a receptacle for the cartridge in an the applicator container, as described herein later. Preferably, the cross-sectional size of the bore 16 is sufficient to permit the elastic compression of the material of the plug 11.

It has been found surprisingly that the bore 16 in the cartridge body 9 also can serve as a vent for the escape of any air or gases that might become trapped near the top surface 14 of the upper base 12 when the volume of personal care composition is placed onto the top surface 14. In such embodiment, the bore 16 extends from the opening 17 in the top surface 14 to the opening 18 in the bottom surface 15 of the plug. This can improve the consistency and effectiveness of the personal care composition mounted onto the cartridge. Preferably, the cross-sectional size of the bore(s) 16 is sufficient to permit the any air or gas to vent from under the personal care composition during application of the composition to the top surface 14 of the upper base 12.

In an alternative embodiment, as illustrated in FIG. 2, a cartridge 110 can include a body that includes a plug 11 and an upper base 12 that has a convex top surface 114.

In another embodiment, the top surface of the upper base can be planar. Configuring the top surface of the upper base to be flat, convex, or planar can enable the user to access and apply the entire volume of the personal care composition that is attached to the cartridge by wiping the surface of the base across the lips, skin, or other body part. In some

embodiments, the top surface 14 or 114 is essentially circular, as shown in FIGS. 1 and 2. However, the top surface of the cartridge configured into any shape to facilitate the loading of the cartridge inside an applicator container or the application of a personal care product.

The personal care composition can be any external-use, non-ingestible substance that can be effectively attached or associated with the top surface of the cartridge, and can be solid, semi-solid, gel-based, or wax-based. The substance can be applied for cosmetic, therapeutic, hygienic, or skin-care applications, including such non-limiting examples as lip balm, lip gloss, lipstick, mascara, foundation, concealers, blemish removers, creams, aloe, lotions, ointments, and deodorants. In some embodiments of the invention, the personal care composition is lip balm.

FIGS. 3 and 4 illustrate a cartridge 10 that includes a volume of a personal care composition 20 attached to an upper base 12 that has a flat top surface 14. Limiting the height of the personal care composition 20 to be shallow relative to the size of the cartridge 10 can additionally reduce the amount of the composition used per cartridge and promote its limited use. The height of the volume of personal care composition 20 can be less than or equal to the maximum length of the top surface 14, where the height of the personal care composition 20 is measured from the uppermost surface of the cartridge base 12. In one example shown in FIG. 3, the height 'H' of the personal care composition 20 on the cartridge 10 is approximately one half of the length 'L' of the flat top surface 14. However, as one skilled in the art would appreciate that the height H and the length L can be varied accordingly. The cartridge 10 can be defined having a vertical center axis, and in some embodiments, the cartridge base 12, the top surface 14 or 15 and the personal care composition 20 can be coaxial with one another. In another embodiment, the entire cartridge, including the personal care composition, can be symmetrical around the vertical center axis, as depicted in FIG. 4.

FIG. 4 illustrates an exploded view of a cartridge 10 comprising the personal care composition 20, with a discardable covering shown as cap 80 configured to be disposed over the personal care composition 20, with the cartridge 10 configured for fitting or placement within an applicator container 50. FIG. 5A illustrates the cartridge 10 comprising the personal care composition 20, without the discardable cap 80, placed within the applicator container 50. FIG. 5B illustrates a sectional view through the loaded cartridge 10 fitted within the applicator container 50. The cartridge 10 is loaded into a receptacle 52 the applicator container 50, the receptacle 52 defined by an upper rim 56. Personal care product 70 comprises the cartridge 10 with the personal care composition 20, secured within the receptacle 52 of the applicator container 50. The receptacle 52 includes an annular interior sidewall 53 that defines an interior void or capturing bore 54 within the receptacle 52. As shown in the sectional view in FIG. 5B, once the plug 11 of the cartridge 10 is fully inserted into the receptacle 54, a lower surface 15 of the upper base 12 sits on top of the upper rim 56 of the applicator container 50. In some embodiments, the top surface of the upper base can be flush with the upper rim of the applicator container. Segment 11c of the cartridge plug 11 is a press-fit against the annular interior sidewall 53 to create the frictional securement between the applicator container 50 and the cartridge 10. The cartridge plug 11 extends approximately halfway into the interior of the capturing void 54 defined by the annular interior sidewall 53. However, those skilled in the art should appreciate that the length of the cartridge plug 11 can be configured so it

extends any distance into the capturing void 54 of the receptacle 52 to frictionally secure the cartridge 10 inside the applicator container 50, including but not limited to reaching the bottom surface 55 inside the receptacle 52. In some embodiments, as shown in FIGS. 5A and 5B, the receptacle 52 on the applicator container 50 can also be coaxial with the body and top surface of the cartridge, as well as the personal care composition.

Furthermore, the means for securing the cartridge body 9 into an applicator container can include a receptacle in the applicator container that is configured to receive and retain the cartridge body within the receptacle. Any frictional means known in the art can also be used to secure the cartridge inside the applicator container. As a non-limiting example, the plug 11 can be press fit into and frictionally engage a portion of the annular interior sidewall 53 of the receptacle 52, securing the cartridge 10 inside the receptacle 52 of the applicator container 50, as shown in FIG. 4. Alternatively, the cartridge body 9 can be secured inside the applicator by any mechanical means known in the art. Non-limiting examples of mechanical means that can be used to secure the cartridge include a snap bead and snap detent mechanism. FIG. 6 shows one embodiment of a plurality of snap beads 213 disposed intermittently around the periphery of the wall of the plug 211. The mechanical means can also include a slide and track mechanism; a finger latch mechanism; a mounting post and receiving slot mechanism; complimentary screw threads; a lever and catch; a twist lock closure; a pair of magnets of opposite polarity; a hook material and a loop material; snap beads and snap detents; kiss locks; a snap stud and snap socket; or a buckle and a clasp.

When a cartridge 10 having a personal care composition 20 attached to a flat top surface 14 is loaded into an applicator container 50, the flat top surface 14 can be flush with, or slightly raised above, the rim of an applicator container, as shown in FIG. 5B. As a result, the entire volume of the personal care composition attached to the cartridge 10 can be used without wasting or losing any of the personal care composition down inside the applicator container and without having to dip a finger down into the applicator container. Those skilled in the art should appreciate that the perimeter of a convex top surface can also be configured to be flush with, or raised above, the rim of an applicator container. Accordingly, cartridges with flat or convex top surfaces facilitate limited-use applications because only a minimal amount of a personal care composition can be attached to, or associate with, the cartridge base without spilling over the edge or creating a mess on the applicator container or the user. Attaching minimal quantities of personal care composition to the top surface of the upper base of the cartridge additionally enables the personal care composition to be concealed inside the applicator container when the personal care composition is not being applied. Concealing the personal care composition 20 from view when not in use is especially desirable when the applicator container is worn as an aesthetic personal accessory or piece of jewelry.

FIGS. 6, 7A-C, and 9 illustrate a cartridge 210 with a plurality of protuberances 30 integrally attached to a flat top surface 214 of the upper base 212. The protuberances can be typically elongated, and/or extend normal to the top surface, and/or extending in parallel to one another. In some embodiments, the protuberances extend parallel to the common axis shared by the body and top surface of the cartridge. The protuberances 30 can be made by molding and can comprise the same material as the base, including but not limited to

resilient materials such as thermoplastic materials or inert synthetic polymers. In some embodiments of the invention, the protuberances can be made of polysiloxane, commonly referred to as silicone.

Protuberances of different lengths can be utilized so the distal ends 31 of each of the plurality of protuberances 30 provide a shaped contact surface 33 from which the user can exfoliate his or her lips or skin during use. The contact surface 33 can be configured into any desired shape from which to exfoliate the lips or skin during application of the personal care composition 20, including but not limited to a domed surface (as illustrated in FIG. 2), a flat surface, an angled surface, or any other desired shape.

The cartridge 10 can also include any number of protuberances 30 in any desired pattern or arrangement to provide a combination of anchoring of the personal care composition 20 onto the cartridge along with exfoliation performance. Additionally, arrangements of protuberances can include protuberances that have a different length, diameter, or durometer than other protuberances in the same arrangement. Protuberances may also be arranged so that some protuberances in the arrangement are tightly packed together while other protuberances are comparatively spaced further apart. A personal care composition that is gel-based or loosely-packed can be attached to a cartridge that includes several protuberances that have a smaller diameter and are tightly arranged. Conversely, solid, waxy, or tightly-packed personal care compositions that can maintain their own shape can be utilized on cartridges that include protuberances that are spaced further apart or have thicker diameters, or on cartridges that do not include protuberances at all. Non-limiting examples of arrangements of protuberances on the top surface include tightly-packed protuberances in rows, concentric circles, or other patterns.

In some embodiments of the invention, the personal care composition can be embedded between each of the plurality of protuberances, anchoring the personal care composition to the cartridge. To more effectively anchor the personal care composition, the length, diameter, firmness, and shape of the protuberances can be tailored by one skilled in the art based on the type and characteristic of the personal care composition. A protuberance can have a length of about 1 to about 15 millimeters, particularly about 3 to about 10 millimeters, and a diameter or longest cross-sectional dimension of about 0.5 to about 5 millimeters, particularly about 1 to about 3 millimeters; and a durometer on the Shore A scale of about 10 to about 70, particularly a durometer on the Shore A scale of about 25 to about 40. The protuberances can be sufficiently firm and resilient to retain their shape when the lip balm is loaded and embedded around the bristles, to retain their shape as the lip balm is applied, and to exfoliate the user's skin or lips as the personal care composition is being applied and depleted. The protuberances should be pliable and overly elastic such that they collapse or lay over onto the surface of a remaining portion of the personal care composition embedded between them as the composition is depleted. The cross-sectional shape of a protuberance can be circular, oval, square, rectangular, other polygon, or any effective shape. Additionally, the protuberances themselves can also be formed into any desired shape or type, including but not limited to blades, bristles, nubs, or nodules. In some embodiments of the invention, the plurality of protuberances comprises a plurality of silicone bristles.

The protuberances 30 have a number of physical and material properties, and care used in a variety of arrangements, to provide value and benefits to the user of the product. The plurality of protuberances can have a rounded,

preferably smooth, distal end 31. In one embodiment, the spacing between the distal ends of adjacent protuberances is at least one protuberance-end diameter, which in one embodiment can range between about 25-40 mil (0.025-0.040 inches), and in another embodiment, be about 30 mil (0.030 inches). Each of the bristles or protuberances 30 has a cylindrical outer shape, tapering slightly (about 5 degrees) outwardly from the distal end 31 to the base end 35 (see FIG. 6), which is attached integrally to the top surface 14 of the upper base 12 through a transition base 37.

In one embodiment of the invention, the density of protuberances or bristles on the top surface of the upper base is at least 20 bristles per square cm, and up to about 60 bristles per square cm, including about 35-45 bristles per square cm.

In an embodiment of the invention, the length of a protuberance, from the top surface of the upper base, to the distal end of the protuberance, can be at least 100 mil (0.010 inch), including at least 150 mil (0.015 inch), and can include 180 mil, 190 mil, and 200 mil.

In an embodiment of the invention, the volume of the personal care composition is typically about 0.5-1.0 ml. In an embodiment of the invention, the ratio of the volume of the personal care composition to the volume of the plurality of protuberances 30 is typically at least 4:1, and up to about 10:1, which can include at least 5:1, or 6:1, or 7:1. In another embodiment, the ratio of the total area that boundaries the plurality of protuberances to the total area of the plurality of base ends of the protuberances, is typically at least 3:1, and up to about 10:1, which can include at least 4:1, such as about 5:1, or about 6:1.

As illustrated in FIG. 7A, the plurality of protuberances 30 can be arranged in a manner that they form the shape of a triangle, with additional protuberances 30 filling in gaps on the flat top surface 214 of cartridge 210A. In contrast, FIG. 7B shows a cartridge 210B having an alternate arrangement of protuberances 30 in a series of concentric circles. FIG. 7C shows a cartridge 210C having another alternate arrangement of protuberances 30 including an outer-most ring 230 of protuberance 30 that have a tighter packing of protuberances 30 in comparison to the intermediate ring 231 and the inner-most ring 232 of protuberances 30. As shown, the width w_1 of the protuberances 30 in the outer-most ring 230 is about the same as the spacing s_1 between adjacent protuberances 30 in the outer-most ring 230. The ratio of the protuberances width w_1 to the spacing s_1 is typically about 1.0 ± 0.2 , and alternatively about 1.0 or greater. In comparison, the width w_2 of the protuberances 30 in the intermediate ring 231, or the inner-most ring 232, is less than the spacing s_2 between adjacent protuberances 30 in the intermediate ring 231, or the inner-most ring 232. The ratio of the protuberances width w_2 to the spacing s_2 is less than the ratio for the outer-most ring 230, and is typically less than 1.0. Without being bound by any particular theory, the more densely packed protuberances in the outer-most ring 230 provide a more robust barrier, or dike or dam, against the flow laterally of the composition 20 through the outer-most ring 230, which helps to control against excessive and unwanted leakage of the composition 20 from the cartridge.

It should be appreciated by those skilled in the art that the example depicted in FIGS. 7A and 7B are non-limiting illustrations only, and that the protuberances may be arranged on the top surface of the cartridge base in any pattern, arrangement, number, length, shape, durometer, or diameter desired or necessary to anchor a particular personal care composition to the cartridge.

11

FIG. 9 illustrates a sectional view of a personal care product 170 that includes a cartridge 210 with a personal care composition 20 embedded between a plurality of integrally-attached protuberances 30 that has been loaded into an applicator container 150. As the personal care composition is applied on the lips or skin of the user and the quantity of the personal care composition attached to the cartridge is depleted, the protuberances become exposed until there is eventually no personal care composition remaining that can be applied.

FIG. 9 also demonstrates a mechanical snap fit between the cartridge 210 and the applicator container 150. The cartridge body 211 can include one or more projections 213 that can be loaded or snapped into one or more notches 156 in the sidewall 153 defining the interior capturing void 154 of the receptacle 152. FIG. 9 shows that the bottom surface 216 of the cartridge body 211 projects approximately half-way into the interior capturing void 154 of the receptacle 152. Nevertheless, the length of the cartridge body 211 can be configured to extend any distance into the interior capturing void 154, including touching the bottom surface 155 of the receptacle 152. Similarly, a cartridge 210 that includes a plurality of integrally-attached protuberances can be configured to be loaded and secured inside the applicator container by any means known in the art, including a frictional securing, as seen in FIG. 4.

In one Example of the cartridge of the invention, the top surface 14 of the upper base 12 has a diameter of 0.55 inch, and the plurality or matrix of bristles has total diameter of about 0.45 inches, and a uniform height of about 0.20 inches.

Although the above examples illustrate cartridges with protuberances integrally attached to a flat top surface of the base, protuberances can additionally be attached to cartridges with top surfaces that are convex, planar, or concave. As with cartridges having a flat top surface, the lengths of each of the plurality of protuberances on a convex top surface can be identical to each other to form a domed contact surface, similar to that shown in FIG. 6. Similarly, a plurality of identical-length protuberances on a concave top surface can form a recessed contact surface. Additionally, the lengths of each of the plurality of protuberances can be appropriately varied on convex or concave top surfaces to provide a flat contact surface, or the lengths can be otherwise varied to create any desired arrangement and layout of the protuberances on the top surface of the cartridge base.

In some embodiments of the invention, the cartridge may additionally include a removable or discardable covering which envelops to protect the personal care composition and keep it sanitary either prior to loading the cartridge into an applicator container or prior to the first application of the personal care composition on the lips or skin of the user. The discardable covering may be configured to any shape necessary to prevent the personal care composition from contacting any surfaces outside of the cartridge, including the applicator container in which the cartridge is loaded, and may include adhesives to ensure a proper seal with the cartridge. The sanitary covering may additionally include a tab or another means known to those skilled in the art to facilitate removal of the sanitary covering from the cartridge.

In another embodiment, the discardable covering can be a rigid or resilient cap. As shown in FIGS. 4 and 8A-8D, the cap 80 includes an upper wall 88, a cylindrical sidewall 89, and an annular lower rim 87 that defines a closed end, and can be configured to envelop or encapsulate the personal care composition 20 and remain in place until the user decides to remove the cap 80. In some embodiments, as

12

shown in FIG. 8C, the cap 80 includes an annular rib 86 that can form a snap fit with a corresponding annular groove 84 on the cartridge base 12 or 212. However, the cap can be configured to be releasably fastened to the cartridge base by any means known in the art.

Additional non-limiting examples of caps that can be utilized to envelop or encapsulate the personal care composition are provided in FIGS. 8A, 8B, and 8D. FIGS. 8A and 8B illustrate a cap 81 that has a cap projection 82 that 10 extends axially from an inner surface of the upper wall 88 and into the personal care composition 20 when the cap 81 is secured to the cartridge base 212 or the personal care composition 20. The cap projection 82 provides a rigid body through which a user can apply pressure to frictionally 15 secure the cartridge into a receptacle of an applicator container without damaging the personal care composition. Conversely, FIG. 8D shows a cap 83 that rests atop the top surface 214 of the cartridge base 212 without projecting into the personal care composition 20. One or more protecting 20 wraps 85 can temporarily secure the annular lower rim 87 of the cap 83 to the perimeter edge 215 of the cartridge base 212. In some embodiments, the protecting wrap 85 is shrink wrap. Any of the caps 80, 81, or 83 may be discarded after 25 initially being removed from the cartridge, or they can be reinstalled after each application to provide an additional layer of protection for the personal care composition when not in use. A cap can be formed out of metallic, thermoplastic, or silicone-based materials. In some embodiments, the cap is plastic.

In some embodiments, where the volume of a personal care composition on a cartridge has been depleted, a fresh quantity of personal care composition can be loaded by hand onto the base of an empty cartridge having a plurality of attached protuberances by swiping or submerging the top 30 surface of cartridge base into a larger volume of the personal care composition. This allows the same cartridge to be reloaded multiple times rather than switching to a new cartridge.

In some embodiments, both pre-loaded and manually-loaded 40 cartridges can be secured in the receptacle of any applicator container configured to receive the cartridge, including commonly-available applicator containers, with such non-limiting examples as lip balm tubes, lipstick applicators, makeup or cosmetic containers, and other dispensing 45 apparatuses, such as the chapstick dispensing apparatus discussed in U.S. Pat. No. 6,283,658 or the freshening ring described in U.S. Pat. Pub. 2013/0014312. Cartridges can also be loaded and secured within the applicator containers of commercially-available personal care products, particularly lip balm products, once their contents have been 50 partially or fully depleted, thereby “recharging” the container for reuse and preventing the user from having to throw away a previously purchased or used applicator container.

Commercially-available personal care products can 55 include, but are not limited to, products having different manufacturing origins, sold at different retailers, or packaged separately from the cartridges of the present invention. Furthermore, cartridges having a plurality of attached protuberances can be secured within receptacles inside commercially-available products that have applicator containers 60 with receptacle sidewalls that extend above the top surface of the cartridge. As a result, personal care composition can be attached to or fixed on an empty cartridge having a plurality of protuberances either prior to loading the cartridge into the commercially-available personal care product's applicator container, or after the cartridge has been 65 secured inside its receptacle.

13

As described above, the personal care composition can be applied by the user by hand directly from the cartridge itself, or after being loaded into an applicator container. Any applicator container known in the art can be adapted to receive and secure the cartridge, including those mentioned above. In some embodiments, the applicator container can be a piece of jewelry or a wearable accessory. Non-limiting examples of jewelry or wearable accessories that can be adapted to be applicator containers can include jewelry includes necklaces, lockets, bracelets, watches, armlets, amulets, bangles, rings, cuff links, broaches, charms, pendants or medallions. The applicator container can also be configured to be mounted or secured onto fixed or portable surfaces, including but not limited to desks, car dashboards, dressers, purses, duffel bags, ID badge holders, or athletic equipment. Applicator containers can be formed from any material or combination of materials, including but not limited to jewelry-grade precious metals such as platinum, gold, or silver; less expensive metals such as aluminum or copper, metal alloys such as steel, molded thermoplastics, wood, ceramics, glass, fabrics, leather, or woven materials.

Applicator containers can also be configured to any desired shape. In some embodiments, an applicator container **50** can further be defined by an outer wall **57**, as shown in FIG. 4, at least a portion of the outer wall defined by a cross-section normal to the common axis has a shape that is elliptical or oval. The elliptical portion **58** of the outer wall **57** can define an elongate or arcuate gripping surface **59** that can be configured to fit between the base of the user's thumb and forefinger during single-handed operation of the applicator container **50**, allowing the user to more easily fasten or unfasten the closure and apply the personal care composition to his or her skin or lips. Applicator containers that are elliptical or oval-shaped can also be configured to rest flat against the chest of a user when the applicator container is worn as a necklace or locket, which can help conceal the applicator container and make it more comfortable to wear.

To further secure the cartridge inside the applicator container, the applicator container can also include a removable closure to protect the loaded cartridge when the personal care composition is not being applied to one's lips or skin. The closure can be frictionally or mechanically fastened to the applicator container by any means known in the art. To mechanically fasten the closure to the applicator container, the applicator container can additionally include a first fastener element that is complementary to a second fastener element that is included on the closure. The first fastener element and the second fastener element can comprise a fastener which releasably fastens the removable closure to the applicator container. Any suitable fastener commonly incorporated onto jewelry or personal accessories may be used, including but not limited to a friction fit, a lever and catch, kiss locks, a twist lock closure, a mounting post and post-receiving slot mechanism, a snap stud and snap socket, snap beads and snap detents, a buckle and clasp, a hook material and a loop material, complementary screw threads, or a pair of magnets of opposite polarity. Additionally, the closure can incorporate ornamental or aesthetically-pleasing design elements to increase the attractiveness of the piece of jewelry as well as conceal the presence of a cartridge inside the applicator container.

As a non-limiting example, FIGS. 10 and 11 illustrate a cover **180** having female screw threads **188** that can be fastened to an applicator container **150** having complimentary male screw threads **158** to form a locket **200**. The cover **180** includes an external loop structure **182** through which a

14

chain, string, lanyard, or a similar structure can be threaded, enabling the locket **200** to be worn as a piece of jewelry. As illustrated by the sectional view of the locket **200** in FIG. 10, the cover **180** includes an interior side wall **184** that defines an interior void **186** inside the cover **180**. The interior void **186** separates the personal care composition **20** from the interior sidewall **184** of the cover **180**, ensuring that neither the locket **200** or items in the external environment contact the personal care composition **20** while it is being stored in between uses.

In some embodiments, a removable closure is separable from the applicator container entirely, as shown in FIGS. 10 and 11. In other embodiments, the closure can be connected to the applicator container by a hinge. Upon releasing the fastener, the closure can be moved away from the applicator container until the user has unimpeded access to apply the entire remaining volume of the personal care composition. Connected closures can be fastened to the applicator container by any of the mechanical fasteners described above.

As described above, the cartridges are intended to contain or hold a limited quantity of a personal care composition. After the personal care composition has been fully depleted from the cartridge that is loaded into a flat container, the cartridge may be removed the container, discarded, and replaced by a fresh cartridge. Cartridges may be removed by any common means known in the art, including but not limited to grasping the upper base of the cartridge and pulling it out of the applicator container, inverting the applicator container, releasing a mechanical fastener between the cartridge and applicator container, or incorporating additional design elements into the container to eject the cartridge, such as a button or a lever. Additional non-limiting examples of ejectors include a threaded rod and a turnwheel or an elevator that controls a platform. Numerous similar design elements can be utilized in the same fashion by those skilled in the art to facilitate removal of a cartridge from other flat containers.

While the present invention has been illustrated by the description of embodiments and examples thereof, it is not intended to restrict or in any way limit the scope of the appended claims to such detail. Additional advantages and modifications of the details of the invention will be readily apparent to those skilled in the art. Accordingly, departures may be made from such details without departing from the scope of the invention.

I claim:

1. An article of manufacture consisting of a personal care product cartridge containing a lip balm composition and configured for mounting in an applicator container, comprising:
  - a rigid or resilient body including a base having a top surface and a bottom surface, and a plug having an annular sidewall extending axially from the bottom surface of the base, and configured for mounting the body of the cartridge into an applicator container;
  - a plurality of resilient, elongated and parallel protuberances integrally attached to and extending from the top surface of the base; and
  - a volume of a lip balm composition at least partially embedded between the plurality of protuberances, to improve anchoring the lip balm composition to the top surface of the body.
2. The personal care product cartridge according to claim 1 wherein the body, the plug, and the top surface of the base are cylindrical and are coaxial around a common axis.

15

3. The personal care product cartridge according to claim 2 wherein the plurality of protuberances extend parallel to the common axis.

4. The personal care product cartridge according to claim 3 wherein the plurality of protuberances are disposed symmetrically around the common axis.

5. The personal care product cartridge according to claim 3 wherein the plurality of protuberances includes a plurality of bristles made of silicone.

6. The personal care product cartridge according to claim 5 wherein the top surface of the base is flat, each of the plurality of protuberances includes a distal end, the plurality of protuberances comprises protuberances that have at least two different lengths, and the plurality of distal ends form an upper contact surface that has a domed shape.

7. The personal care product cartridge according to claim 6 wherein the top surface of the base is planar.

8. The personal care product cartridge according to claim 1 wherein the body has a cylindrical bore formed axially within the plug.

9. The personal care product cartridge according to claim 8 wherein the bore extends through both the bottom surface of the plug and the top surface of the base.

10. The cartridge according to claim 9 wherein the length of the protuberances is about 3 millimeters (mm) to 10 mm, and a diameter or longest cross-sectional dimension of about 1 mm to 3 mm.

11. The personal care product cartridge according to claim 1, wherein a maximum height of the volume of lip balm composition on the top surface is less than or equal to a maximum length of the base, where the maximum height of the volume of lip balm composition is measured from an uppermost surface of the base.

12. The personal care product cartridge according to claim 1 further including a discardable covering that envelops the lip balm composition, where the discardable covering is configured to be removed:

- a) prior to loading the cartridge into the applicator container, or
- b) after loading the cartridge into the receptacle, and prior to the first application of the lip balm composition on the lips or skin of the user.

13. The personal care product cartridge according to claim 12, wherein the discardable covering includes a rigid or resilient cap that is mechanically or frictionally secured to the base of the cartridge or to the lip balm composition.

14. The personal care product cartridge according to claim 13, wherein the cap further includes:

- a) a closed end defined by an upper wall having a periphery and an inner surface,
- b) a cylindrical sidewall extending from the periphery of the upper wall, and
- c) at least one cap projection extending axially from the inner surface of the upper wall, where the cap projection extends into the lip balm composition when the cap is secured to the base of the cartridge or to the lip balm composition.

15. A personal care product comprising the personal care product cartridge according to claim 1, an applicator container, and a means for securing the body of the personal care product cartridge releasably into a receptacle of the applicator container.

16

16. The personal care product according to claim 15 where the means for securing the cartridge body includes a cylindrical bore in the applicator container defining a receptacle including an upper rim that is configured to receive and retain the cylindrical body.

17. The personal care product according to claim 16 wherein the cartridge body is retained in the bore by a mechanical fastener.

18. The personal care product according to claim 16 wherein the top surface of the cartridge is flush with or raised above an upper rim of the receptacle.

19. The personal care product according to claim 16 wherein the applicator container further includes an outer wall, wherein a portion of the outer wall defined by a cross-section normal to the common axis has a shape that is elliptical or oval, to provide the applicator container with an elongate or arcuate gripping surface.

20. The personal care product according to claim 19, wherein the applicator container further comprises a removable closure and a fastener to releasably fasten the removable closure over the receptacle.

21. The personal care product according to claim 20, wherein the closure is configured to give the user unimpeded access to apply the entire volume of lip balm composition when the removable closure is removed from over the receptacle.

22. The personal care product according to claim 21, wherein the closure is separable from the container.

23. The personal care product according to claim 21 wherein the closable applicator container is a piece of jewelry or a wearable accessory.

24. The personal care product according to claim 23 wherein the applicator container further includes an ejector for controllably ejecting the cartridge from the applicator container, wherein the ejector is selected from the group consisting of a threaded rod and turnwheel or an elevator platform.

25. The personal care product cartridge according to claim 1 wherein the length of the protuberances is about 3 millimeters (mm) to 10 mm, and a diameter or longest cross-sectional dimension of about 1 mm to 3 mm.

26. A personal care product cartridge containing a lip balm composition and configured for mounting in an applicator container, comprising:

- a) a rigid or resilient body including a base having a top surface, wherein the body and the top surface of the base are cylindrical and are coaxial around a common axis,
- b) a plurality of resilient, elongated and parallel bristles made of silicone, integrally attached to and extending parallel to the common axis from the top surface of the base, wherein each of the plurality of bristles includes a distal end, and the plurality of distal ends form an upper contact surface that has a domed shape, and
- c) a volume of the lip balm composition at least partially embedded between the plurality of protuberances, to improve anchoring the lip balm composition to the cartridge.
